CLOSET FLANGE AND TEST CAP

Frank F. Sosaya, Santa Fe, N. Mex.

Application February 1, 1949, Serial No. 73,979

2 Claims. (Cl. 285—33)

1

This invention relates to closet flanges, and more particularly to a closet flange having an integral, knock-out test cap therein.

It is among the objects of the invention to provide an improved flange for receiving and supporting the upper end of the waste pipe elbow for a toilet bowl and for receiving the hold-down bolts for the bowl, which flange has a reinforced, elbow-receiving collar providing space for adequate packing between the elbow and the flange, and has over the flange end of such collar a continuous wall providing a knock-out test cap which obviates the use of separate test caps formed of rubber or other suitable material, and not only seals the end of the waste pipe elbow, so that the plumbing can be pressure tested prior to the installation of the toilet bowl, but will keep dirt, debris and loose articles out of the plumbing during construction of the building and prevent the escape of sewer gas into the building after the waste plumbing has been connected with the soil pipe and before the toilet bowls are installed and the water connected, which is so constructed that the knock-out test cap can be quickly and easily removed when it is desired to install the toilet bowl, and which closet flange and knock-out test cap is of simple, one-piece construction, economical to manufacture, and easy to install.

Other objects and advantages will become apparent from a consideration of the following description and the appended claims in conjunction with the accompanying drawing, wherein:

Figure 1 is a top plan view of a closet flange illustrative of the invention with a fragmentary portion of a waste pipe elbow attached thereto;

Figure 2 is a side elevation of the closet flange and elbow fragment illustrated in Figure 1, a portion being broken away and shown in cross-section to better illustrate the construction thereof; and

Figure 3 is a diametrical cross-section of the closet flange with the knock-out test cap removed, showing fragmentarily and also in cross-section, the waste pipe elbow and the toilet bowl operatively associated with the closet flange.

With continued reference to the drawing, the closet flange, generally indicated at 10, comprises a cylindrical collar 11 having an external reinforcing bead 12 around one end, and an outwardly-extending annular, external flange 13 around its opposite end. The flange 13 extends outwardly to overlie the floor 14 around the opening 15 provided in the floor for the collar of the toilet flange, and is provided with radially-directed, angularly spaced-apart slots or notches

2

16 opening to its outer edge to receive the head ends of hold-down bolts 17 by means of which the toilet bowl, generally indicated at 18 in Figure 3, is secured to the flange. The under side 5 of the flange 13 is recessed at each side of each of the notches 16, as indicated at 19, to provide sufficient space for the bolt heads 20, so that the bolts may be slid into the notches with the flange 13 resting upon the upper surface of the floor 14.

10 A thin end wall 21 continuous with the flange 13 extends across the flanged end of the collar 11, and this end wall is provided with respective circular grooves 22 and 23 in its outer and inner surfaces to provide, within such grooves, a circular knock-out test plug which will effectively close the upper end of the flange unit before the toilet bowl is assembled with the flange, and which may be easily knocked out and removed when it is desired to install the toilet bowl. The 15 circular grooves 22 and 23 have a diameter substantially equal to the inside diameter of the waste pipe elbow 24, the upper end of which is received in the flange collar 11.

The collar 11 has an inside diameter greater 25 than the outside diameter of the elbow 24, and the upper end of the elbow is inserted into the collar to bear against the inner side of the end wall 21 of the closet flange. The elbow is made substantially concentric with the collar and packing 26

30 of suitable material, such as oakum, is packed into the annular space between the elbow 24 and the collar 11, and a lead seal 26 is then poured in and tamped or peened to a tight sealing condition. The packing 25 and lead seal 26 are applied with the closet flange 10 and elbow 24 inverted from their normal or operative position. After the elbow has been thus sealed into the collar of the flange, the assembly is righted and the elbow positioned so that the collar will 35 extend through the opening 15 in the floor.

The knock-out plug within the circular grooves 22 and 23 is left in position during the construction of the building and until it is desired to install the toilet bowl. At that time, the knock-out plug is broken free of the remainder 40 of the closet flange by striking it with a hammer, after which the boss 27 of the toilet bowl can be inserted through the opening provided by removing the knock-out test plug. The bolts 17 are positioned in the notches 16 before the toilet bowl is finally positioned, so that the bolts will project through the bolt-receiving apertures 28 in the toilet bowl base flange 29, and the bowl is then brought to rest upon the floor, and the 45 nuts 30 are applied to the bolts 17, thus com-

3

pleting the operation of installing the toilet bowl.

The above-described toilet flange construction provides a simple, one-piece member including both a closet flange and a knock-out test plug for the upper end of an associated waste pipe elbow, which combined closet flange and test plug can be easily manufactured by a simple casting operation, and is no more expensive than conventional closet flanges in which a separate rubber test plug must be used to close the upper end of the waste pipe elbow for testing the plumbing and to keep debris, et cetera, out of the plumbing during building construction.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. In combination with a waste pipe elbow, a combined closet flange and knock-out test plug comprising a cylindrical collar loosely receiving one end of said waste pipe elbow, an annular external flange surrounding one end of said collar and having angularly spaced-apart, radially-directed notches therein for receiving toilet bowl hold-down bolts, and a thin end wall continuous with said flange overlying said one end of said collar, said end wall having circular grooves in the inner and outer surfaces thereof adjacent the inner edge of said collar, said grooves having a common diameter smaller than the diameter of said collar and substantially equal to the inside diameter of said waste pipe elbow to provide a circular knock-out plug closing said one end of

4

said collar, said closet flange being formed of a frangible material and said grooves having a substantially V-shaped cross-section to provide a smooth edge around the opening provided by removing said knock-out test plug.

2. In combination with a waste pipe elbow, a combined closet flange and knockout test plug comprising an integral structure including a cylindrical collar portion circumferentially receiving one end of said waste pipe elbow and a packing surrounding said one end, an annular external flange portion projecting perpendicularly from one end of said collar portion and having annularly spaced apart notches therein for receiving toilet hold-down bolts, and a thin end wall having its outer surface continuous with the outer face of said annular flange overlying and closing said one end of the collar portion, said end wall having concentric grooves of the same diameter disposed one in the inner and one in the outer surface thereof to weaken said end wall around a circular knockout plug portion which is concentric with and smaller than said one end of said collar portion to provide within said collar portion when the knockout plug portion is removed, an internal annular flange portion constituting an abutment for said one end of said waste pipe elbow and said packing.
